UNITED STATES PATENT OFFICE.

JOHN B. BUSHNELL, OF BERKELEY, CALIFORNIA, ASSIGNOR TO N. R. HARRIS AND M. C. HARRIS, COPARTNERS, DOING BUSINESS AS HARRIS ELECTRIC COMPANY, OF SAN FRANCISCO, CALIFORNIA.

DYNAMO-ELECTRIC MACHINE.

Application filed February 27, 1922. Serial No. 539,387.

To all whom it may concern:

Be it known that I, JOHN B. BUSHNELL, a citizen of the United States, and a resident of the city of Berkeley, in the county 5 of Alameda and State of California, am the inventor of a new and useful Dynamo-Electric Machine, of which the following is a specification.

This invention relates to a dynamo electric 10 machine, and more particularly to an inductor generator. Such generators are now used extensively in automobile lighting equipment, and are arranged to be driven from the shaft of the engine. Since the engine speed necessarily varies considerably, 15 the generator is so arranged that speed variations do not cause its operating characteristics to be varied materially. This result has been obtained by various expedients, 20 such as by working the iron in the magnetic circuit above the saturation point, by making the generating coil or coils have a relatively high resistance, or by utilizing the reaction of the current flowing in these 25 coils upon the magnetic circuit. It has been found that the best regulating effects are obtained when the lights are all arranged in series on a single circuit; that is, when a straight series connection is used. This arrangement has the serious disadvantage that 30 when any one of the lights happen to be out of order, the entire generator is disconnected and out of use. It is one of the objects of my invention to make it possible for 35 an engine driven generator to supply a plurality of circuits which are capable of independent operation.

In order to obtain this result, I provide 40 a single magnetic circuit in which there are a plurality of gaps in series, these gaps being bridged by rotating inductors. With each gap or opening is associated one or more generating coils, and I have found in such an arrangement that the circuits for any of 45 these independent coils may be made or broken without interfering materially with the operation of the other coils. This arrangement is very compact, since virtually a single magnetic circuit serves for the equivalent of a plurality of generators. It is thus another object of my invention to provide a generator having relatively small 50 weight for its capacity.

My invention possesses other advantageous features, some of which, with the foregoing, 55 will be set forth at length in the following specification where I shall outline in full those forms of the invention which I have selected for illustration in the drawings accompanying and forming part of my present 60 specification. In the drawings I have shown several embodiments of my invention, but it is to be understood that I do not limit myself to those forms, since the invention as expressed in the claims may be embodied in 65 other forms as well.

Referring to the drawings:

Figure 1 is a side view, partly sectional, 70 of a complete inductor generator embodying my invention;

Fig. 2 is a sectional view taken along the line 2—2 of Fig. 1;

Fig. 3 is a diagrammatic view of the magnetic circuits of the generator illustrated in 75 Figs. 1 and 2;

Fig. 4 is a diagrammatic view of a modification of my invention;

Fig. 5 is a diagrammatic view of a further modification;

Fig. 6 is a diagrammatic view of the generator coils; and

Fig. 7 is a wiring diagram of a lighting 80 system embodying my invention

As is usual in inductor alternators, there is a magnetic circuit, part of which is stationary and a part movable. The movable portion is usually the inductor, and its movement past the pole faces causes a variation in the number of lines of force threading a generating coil. In the modification shown 85 in Figs. 1, 2 and 3, a plurality of stationary permanent bar magnets 11 is used to supply the magnetizing force. These magnets 11 have opposed pole tips 12, 13, 14 and 15, and are arranged in opposed relation to each other, as clearly shown in Fig. 3. The magnets 11 are arranged to assist each other; that is, if the tip 12 forms a north pole, then tip 13 forms a south pole. In this arrangement a plurality of gaps in series is formed 90 in the magnetic circuit, in which gaps are located the rotatable inductors 16 and 17. These inductors by their movement cause a variation in the magnetic lines of force threading the stationary generating coils 18 95 and 19, which are located in slots in the

pole tips 12, 13, 14 and 15. The axes of coils 18 and 19 are at right angles to the axes of rotation of the inductors 16 and 17, opposite sides of the coil being located in opposite pole tips. The slots accommodating these coils are purposely made wide enough to prevent appreciable magnetic leakage between the two halves of the pole tips. Assuming rotation in a counter-clockwise direction, and that the pole tip 12 forms a north pole while tip 13 forms a south pole, the direction of the flux threading coil 18 will be downward. However, after the inductor has rotated through 90° , into the position shown by the dotted lines, the direction of the flux will be reversed as regards the coil 18. This reversal takes place when the inductor 18 leaves the position opposite the upper part of tip 12 and takes a position opposite the lower part of tip 12. The variation in the direction and amount of the magnetic flux induces an E. M. F. in the coil 18. Movement of the inductor 16 through another 90° will again reverse the flux for then a position similar to the full line position is again obtained. The upper and lower portions of each of the pole tips extend through an arc of substantially 45° , and the slots formed in them also extend substantially the same amount. In this way the portions of the pole tips are uniformly spaced around a circle, and complete uniform electromotive force waves are obtained for every half-revolution.

35 The generation of an electromotive force in coil 19 is produced in a manner entirely similar to that already described in connection with coil 18. Coils 18 and 19 may, if desired, be connected to the same load, or they 40 may preferably be used to supply separate lamp loads. Thus each headlight lamp may be supplied with current from separate coils. In this way, the two headlight lamps may be independently controlled or operated.

45 Preferably the two inductors 16 and 17 are driven at the same speed, usually by the engine shaft. These inductors may be displaced relatively to each other, as indicated in Fig. 3, so that while one of them does not 50 serve as a good magnetic bridge between the pole tips, the other one is in the proper position for conducting the lines of force from one tip to the other. In this way there is never more than one large air gap in the 55 magnetic circuit, and therefore the same magnetic strength is obtained as if there were but one inductor and but one gap; thus while inductor 17 is horizontal, and not serving to conduct lines of force from one 60 pole tip to the other, the inductor 16 is in such a position that it connects the upper portion of pole tip 12 with the lower portion of pole tip 13. The same magnetic circuit is advantageously used for a plurality of generators, producing E. M. F.'s

that are out of phase with each other, and there is an attendant saving in the cost and size of a machine for a given output.

However, since the current in the generating coils necessarily lags somewhat behind the electromotive force due to the self induction of the circuit, one of the two coils 18 and 19 acts at certain portions of a cycle, to assist the building up of magnetism in the magnetic circuit. As a matter of fact, the balancing of the various magnetomotive forces is such, due to saturation effects and the reaction and resistance of the coils, that even upon a wide range in engine speed or in the resistance of the external circuit, substantially the same current output is obtained. The theoretical analysis of the regulative action is obviously so complex that no attempt will be made here to discuss it.

The actual mechanical embodiment of the form of my invention described hereinbefore is shown to best advantage in Figs. 1 and 2. The inductors 16 and 17 are each mounted on shafts such as 20 which are supported in roller or ball bearings carried by the housings 21 and 22. Each of the shafts carries a pinion 23 securely fastened to the shaft, with which a gear 24 is arranged to mesh. This gear rotates about an axis coincident with that of the shaft 25 of the machine, which is adapted to be driven by the engine. This shaft is appropriately journaled in the housing members 26 and 27, which encase all of the operating parts of the generator. The member 27 is itself split lengthwise for ease in assembling and manufacture. The driving connection between the shaft 25 and the gear 24 includes a friction clutch 28, one part 30 of which is slidably but non-rotatably mounted upon the shaft 25, and the other part is made integral with a hollow sleeve-like member 29 encompassing the shaft. This member 29 is securely fastened to the wheel 24, and is itself journaled for rotation in an aperture or bore formed in the interior of casing member 27. The fastening of member 29 to gear 24 may be accomplished in any appropriate manner. For example, a bushing 51 having an exterior surface journaled in frame 27 can be fastened to member 29 by the aid of the key 52, and gear 24 may likewise be held on member 29 by the aid of this key. In order to prevent axial movement of parts 24 and 51, a ring 50 can be used, held to sleeve 29 by a set screw 49.

The clutch faces on parts 29 and 30 may be made to engage or disengage by means of a lever 31, fastened to a shaft 32 which is pivoted within the casing member 26. This shaft carries a fork 33 which engages within the groove 34 of the member 30 so as to slide it axially upon the shaft 25.

The permanent magnets 11 are conven-

iently supported in the member 27, in panel-like pockets formed by the ribs 35. The pole tips 12, 13, 14 and 15 are imbedded in this casing member also, as shown most clearly in Fig. 2. This casing member must of course be made of non-magnetic material so that the magnetism will not be shunted improperly by it. The coil 18 is made in two sections and the end portions of these 10 sections are turned up at right angles from the side portions which fit into the slots in the pole pieces. A diagram of the coil is illustrated in Fig. 6, the parallel sides 36 forming the active part of the coil.

15 The casing members 26 and 27 are appropriately fastened together as by the bolts 37, and the arrangement is such that a compact, practically dust-proof covering for the working parts is obtained.

20 The important conception of utilizing a single magnetic structure serving as a series magnetic circuit for a plurality of generating units may readily be extended to accommodate even dissimilar units. Thus in 25 Fig. 4, in addition to the two inductor type units 38 and 39, a high tension magneto unit 40 may be placed in the same magnetic circuit. This latter unit may have a wound rotatable armature member 41, and may be 30 used, for example, for the ignition circuits of the gasoline engine. If used in this way, the unit 40 must have its armature rotated at the same speed as the engine shaft.

Another embodiment of my invention, in 35 which three inductor generator units are used, is diagrammatically shown in Fig. 5. It is of course evident that the units using the same magnetic circuit in series may be dissimilar in size or kind, the better to fit 40 each of them for the service demanded.

The adaptation of my invention in an automobile lighting system produces certain beneficial results. Such an adaptation is illustrated in the wiring diagram of Fig. 7. 45 Here the generating coil 18 is connected to a head light 42 and tail light 44, while another generating coil 19 is connected to the other headlight 43 and another tail light 45.

Appropriate connecting devices 46 and 47 50 located in a convenient position may also be supplied. The magnetic circuit of the generator is omitted from the drawing, and

instead the rectangle 48 is intended to represent the complete generator.

In a system such as illustrated in this 55 figure, the total failure of the lighting system is highly improbable. There is furthermore no danger that the tail light will not be lit, so long as one of the headlights is in operation.

I claim:

1. In an inductor alternator, a pair of magnets having their unlike poles arranged opposite each other, means forming poles near the extremities of the magnets so as to 65 form two gaps in series, a magnetic rotor in each gap, and windings associated with the magnetic structure.

2. In an inductor alternator, a pair of magnets having their unlike poles arranged 70 opposite each other, slotted pole tips carried near each extremity of the magnets so as to form two gaps in series, a rotatable inductor in each of the gaps, and generating coils disposed in the slots in the pole tips.

3. In an inductor alternator, a pair of sets of permanent magnets arranged opposite each other, pole tips carried at each extremity of the magnets so as to form two gaps in series, a rotatable inductor in each 80 of the gaps, and coils disposed in slots formed in the pole tips.

4. In an inductor alternator, a pair of sets of permanent magnets arranged opposite each other, pole tips having slots carried at each extremity of the magnets forming two gaps in series, a coil associated with each 85 gap, and a rotatable inductor in each gap.

5. In an inductor alternator, a pair of sets 90 of permanent magnets arranged opposite each other, pole tips having slots carried at each extremity of the magnets forming two gaps in series, a coil associated with each gap, inductors mounted for rotation within 95 the gaps, and a common means for rotating both inductors, said inductors being so arranged that the electromotive forces generated in the coils are out of phase with each other.

In testimony whereof, I have hereunto set my hand.

JOHN B. BUSHNELL.
